(57) **CLAIM**

The ornamental design for a locking apparatus, as shown and described.

DESCRIPTION

FIG. 1 is a top perspective view of a locking apparatus in accordance with the present design;

FIG. 2 is a bottom perspective view thereof;

FIG. 3 is a back view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken lines are for illustrative purposes only and form no part of the claimed design. The shading represents contour of the claimed design.
